WATER STATION

Herbert L. Shivek, Brookline, Mass., assignor to Serv-O-Lift Corporation, Boston, Mass., a corporation of Massachusetts

Filed Nov. 27, 1959, Ser. No. 58,485

Term of patent 14 years

(Cl. D67—4)

FIG. 1

FIG. 2

FIG. 3

Fig. 1 is a view in elevation of a water station showing my new design;

Fig. 2 is a corresponding plan view; and

Fig. 3 is a view in side elevation.

The vertical shading represents springs visible through slots in the side of the casing of the device.

The back of the station is a plain, unbroken panel and both sides of the station are of the same appearance.

I claim:

The ornamental design for a water station, as shown and described.
